(57) **CLAIM**

The ornamental design for a flag stick reflector insert, substantially as shown and described.

DESCRIPTION

FIG. 1 is a perspective view of the flag stick reflector insert showing my design;

FIG. 2 is a side plan view of the insert shown in FIG. 1; FIG. 3 is a side view of the insert shown in FIG. 1, with the insert rotated approximately 72° from the view shown in FIG. 2;

FIG. 4 is a side view of the insert shown in FIG. 1, with the insert rotated approximately 72° from the view shown in FIG. 3;

FIG. 5 is a side view of the insert shown in FIG. 1, with the insert rotated approximately 72° from the view shown in FIG. 4;

FIG. 6 is a side view of the insert shown in FIG. 1, with the insert rotated approximately 72° from the view shown in FIG. 5;

FIG. 7 is a top view of the insert shown in FIG. 1, the bottom view being a mirror image of the top view; and,

FIG. 8 is a perspective view of the insert of FIG. 1 in a use state, with a flag stick shown using broken lines where the broken lines are for illustrative purposes only and form no part of the claimed design.
